UNITED STATES PATENT OFFICE.

CHRISTIAN A. FISCHER, OF GRAND FORKS, NORTH DAKOTA.

MARKER.

1,336,029.

Specification of Letters Patent.

Patented Apr. 6, 1920.

Application filed April 30, 1919. Serial No. 293,587.

To all whom it may concern:

Be it known that I, CHRISTIAN A. FISCHER, a citizen of the United States, residing at Grand Forks, in the county of Grand Forks and State of North Dakota, have invented certain new and useful Improvements in Markers, of which the following is a specification.

This invention seeks to provide a simple, inexpensive and efficient device whereby tickets of admission to places of amusement may be easily stamped to indicate that the war tax levied thereon has been paid and the date of the payment. The invention also seeks to provide a device for the stated purpose which may be easily secured in a fixed position and which will be so constructed that the ticket to be stamped may be easily guided into the stamping position and the invention also seeks to provide a device in which the stamping or printing member may be readily adjusted so as to secure accuracy in the date. Other incidental objects will appear in the course of the following description.

In the accompanying drawings:

Figure 1 is a perspective view of my improved marker in position for use;

Fig. 2 is a similar view showing the members separated but in position to be fitted;

Fig. 3 is a longitudinal section;

Fig. 4 is an end view.

In carrying out my invention, I employ a base member consisting of a U-shaped plate 1 having countersunk openings 2 in its back plate whereby screws or other fastening devices may be inserted into a desk, a standard or other fixed support. The ends of this base member are open, as clearly shown in Fig. 2, and at its lower end its side members are provided with inwardly projecting lips or lugs 3 which form stops for the roller-carrying member. At the free edges of the side members are inwardly projecting longitudinal flanges 4 which serve as guides and retainers for the roller-carrying member. A leaf spring 5 is secured at its upper end to the back plate of the base member and the lower end of this spring projects inwardly or forwardly, as shown in Fig. 2. The roller-carrying member consists of a box 6 having an opening 7 in its front side near one end whereby to permit the ready application of additional ink to the inking pad 8 which is disposed

immediately adjacent said opening and is preferably a roller having a surface of felt or other material, the spindle or axle 9 of the roller being mounted in countersunk openings 10 in the side of the box 60 whereby it will be held in proper position and may rotate freely. The side members of the box 6 are of such dimensions that they will fit closely but slidably within the base member between the back plate of the 65 same and the flanges 4 and the open construction of the base member imparts a slight resiliency thereto so that it will yield sufficiently to permit the ready entrance of the box but will engage the box so closely 70 that it will be firmly held in its operative position. It will be readily understood that the box is inserted from the upper end and will be supported by the engagement of its lower end with the lips or lugs 3. A printing roller 11 is fitted within the lower portion of the box and has its axle or spindle 12 mounted in countersunk openings 13 in the sides of the box, the parts being so proportioned that the printing surfaces upon 75 the roller 11 will bear upon the inking roller and receive ink therefrom. The upper end 14 of the box 6 is free of the side members thereof; but preferably integral with the front plate of the same and the inner 80 edge of its top member is turned downwardly to provide a guiding rib or flange 15 which is spaced from the back plate of the base member so as to furnish a mouth or inlet through which the end of the ticket 90 to be stamped may be inserted, the flange holding the ticket out of contact with the inking roller as will be readily understood on reference to Fig. 3. The printing roller in the illustrated embodiment of the invention is provided upon its surface with an annular band 16 upon which is an inscription indicating that the tax has been paid and at each side of this printing band is an annular rib 17 which will imprint a straight line upon the ticket as will 95 be readily understood. Upon reference to Fig. 4 more particularly it will be noted that the printing band 16 and the ribs 17 are disposed nearer one end of the printing roller 100 and near the other end thereof I provide type faces or blocks 18 which are intended to imprint the date upon the ticket. As shown most clearly in Fig. 3, these types are preferably rectangular so as to fit within 105 110

rectangular sockets in the roller and are removable so that the type may be changed daily and, therefore, the correct date always imprinted upon the ticket.

5 The manner of using the device will, it is thought, be readily understood. The base member is secured in position where it will be convenient to the ticket seller and in the drawings has been shown in an upright 10 position. It is to be understood, however, that it may be secured upon the top of a desk and that the terms "upper" and "lower" as used in this description are relative only and not restrictive and are used 15 merely for convenience in referring to the drawings. After the base member has been secured in place, the box 6 is inserted therein so as to slide against the lips or lugs 3 and thereby be properly positioned within 20 the base member, the printing roller being brought adjacent the free end of the spring 5 and the guiding lip or flange 15 being disposed within the entrance end of the base member. The tickets in actual practice are furnished in continuous strips 25 wound upon reels and each ticket is detached as an admission is sold. The end of a strip of tickets is inserted between the back plate of the base member and the 30 guiding lip or flange 15, as shown in Figs. 1 and 3 and is pushed through the device so that it will be held against the printing roller by the spring 5 and the free end of the spring may be pressed against the back 35 plate when the end of the strip is being inserted, if so desired, so that the ticket will not be forced into the bight between the inking and printing rollers but will pass through the device in such position that its 40 free end may be easily grasped beyond the marker and the strip then drawn through the same as the tickets are needed. After the strip has been placed in position within the marker, as shown in Fig. 3, the spring 45 5 will press the tickets against the surface of the printing roller and the frictional contact will cause the roller to rotate as the tickets are withdrawn. As the roller rotates, the successive points of the printing 50 surface will be brought into contact with the back of the ticket and, consequently, the proper imprint made thereon.

The device is exceedingly simple in the 55 construction and arrangement of its parts and is not apt to get out of order. It is easily operated and requires no attention on the part of the ticket seller, except possibly to occasionally replenish the ink on the inking pad or roller. While the device, as 60 stated, is intended more particularly for imprinting upon theater tickets an inscription denoting that the war tax has been paid and the date of payment, it will be understood, of course, that its field of usefulness 65 is not restricted to this particular purpose

and it may be used for making other imprints upon other articles.

Having thus described the invention, what is claimed as new is:

1. A device for the purpose set forth comprising an open-ended holder, a casing slidably fitted within the holder through one end thereof and spaced from the back of the same to permit passage of a strip to be printed, the sides of the holder guiding the strip, 75 and printing mechanism carried by the casing to act upon the strip drawn over the back of the holder.

2. A device for the purpose set forth comprising a holding member consisting of a U-shaped plate having open ends and provided at one end with inwardly projecting lips and at its front side with retaining flanges, a casing slidably fitted within the holder and impinging against the said lips, 85 and printing mechanism carried by said casing.

3. A device for the purpose set forth comprising a holding member having open ends and provided at one end with inwardly 90 projecting lips, a casing open at one end and at one side slidably fitted within the holder and engaging against said lips, printing mechanism carried by said casing, and a presser member within the holder arranged to coöperate with the printing mechanism.

4. A device for the purpose set forth comprising an open-ended holder, a casing slidably fitted within said holder, printing 100 mechanism carried by said casing, and a leaf spring secured at one end to the holder and having its free end projecting toward the printing mechanism.

5. A device for the purpose set forth comprising a holding member, a casing removably fitted within the holding member and spaced from the holding member to permit passage of a strip to be printed, a printing roller mounted within the casing, an inking 110 member mounted within the casing and in contact with the printing roller, and a presser on the holder arranged to hold the strip to be printed against the printing roller.

6. A device for the purpose set forth comprising a holding member, a casing removably fitted within the holding member and provided with an opening in its front face near one end, an inking roller mounted in 120 the casing adjacent said opening, and a printing roller mounted in the casing and in contact with the inking roller.

7. A device for the purpose set forth comprising a holding member having open 125 ends, a casing fitted within the holder and provided at one end with a cover having an inwardly turned guiding lip, printing mechanism mounted within the casing below said guiding lip, and a presser member 130

on the holder below the lip and arranged to maintain the strip to be printed in contact with the printing mechanism.

8. A device for the purpose set forth comprising a holder, a casing removably fitted in the holder, printing mechanism within the casing comprising a roller having a plu-

rality of sockets and type removably fitted in said sockets, and a presser member on the holder arranged to maintain engagement between the types and the strip to be printed. 10

In testimony whereof I affix my signature.
CHRISTIAN A. FISCHER. [L.S.]
